Primary Examiner — Brandon M Rosati*Assistant Examiner* — Lauren D McVey(74) *Attorney, Agent, or Firm* — Patterson & Sheridan, LLP(57) **CLAIM**

The ornamental design for a wireless base station, as shown and described.

DESCRIPTION

FIG. 1 is a top right perspective view of a wireless base station, showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines immediately adjacent the shaded areas represent the bounds of the claimed design while all other broken lines are directed to environment and are for illustrative purposes only; the broken lines form no part of the claimed design.
